(57) **CLAIM**

The ornamental design for a paint stirrer attachment as shown and described.

DESCRIPTION

FIG. 1 is a front perspective view of a new design for a paint stirrer attachment.

FIG. 2 is a front view of a new design for a paint stirrer attachment.

FIG. 3 is a rear view of a new design for a paint stirrer attachment.

FIG. 4 is a left side view of a new design for a paint stirrer attachment.

FIG. 5 is a right side view of a paint stirrer attachment.

FIG. 6 is a top view of a new design for a paint stirrer attachment; and,

FIG. 7 is a bottom view of a new design for a paint stirrer attachment garment.

The broken lines showing portions of the paint stirrer attachment in the drawing form no part of the claimed design.
